UNITED STATES PATENT OFFICE.

NORMAN DE WIND, OF CHICAGO, ILLINOIS.

PAVEMENT.

Application filed March 8, 1920. Serial No. 363,998.

To all whom it may concern:

Be it known that I, NORMAN DE WIND, a subject of the King of Great Britain, residing at Chicago, in the county of Cook and 5 State of Illinois, have invented certain new and useful Improvements in Pavements, of which the following is a specification.

My invention relates to road pavements and the like and concerns more particularly, 10 but not exclusively, structures of this character having an upper course or top stratum of concrete including comparatively thin grouting when applied. Concrete and other pavements have been laid to a considerable 15 extent, but all of them seem to have certain defects which it is highly desirable to overcome and it is the object of this invention to accomplish such results.

Stated in a general way, the leading aim 20 and prime purpose of this invention is the provision or method of laying a pavement which will be comparatively economical to construct, which will require a minimum amount of cement in its laying, which will 25 be unlikely to crack or break under variations in temperature and climatic conditions, and which may be comparatively easily repaired.

To this end the liquid portion or grouting 30 of the wearing or top course of the pavement is prevented from leaving such stratum when it is laid by reason of a thin retentive layer of suitable material on top of an underlying foundation of compacted or rolled broken stone or the like. Thus the top layer 35 comprises a body of concrete whose strength is retained because of the proper retention therein of its cement ingredient, and such stratum is free from any substantial 40 interlocking engagement with the other portions of the pavement beneath it, but, of course, it rests upon and is supported by them and, consequently, it is free to expand and contract by itself without interference 45 from the other sections of the pavement, with the result that danger of cracking or breaking is greatly reduced, if not entirely eliminated.

To enable those skilled in this art to fully 50 understand the invention, both from structural and functional standpoints, I have illustrated in the accompanying drawing forming a part of this specification in cross-section and perspective one style or form of 55 embodiment of the invention, and to this drawing reference should be had in connec-

tion with a consideration of the following detailed description of the pavement and its method of production.

In laying such an improved and novel 60 type of pavement, if a special foundation course or stratum is employed, which is not always necessary because certain kinds of clay or dirt may be rolled hard to form such supporting base for the pavement, a cambered or crowned layer 10 of broken stone, gravel, cinders, slag, or other suitable material or materials of a sufficient thickness, for example 4 to 12 inches, or other depths, depending upon the width of the roadway, 70 is rolled to render it very firm and compact, curbing 11, 11 being employed at the sides of the roadway if desired. The thickness of such bottom stratum necessarily depends upon the nature of the traffic over the pavement and the load and weights to which it is 75 likely to be subjected.

On top of such foundation layer I then provide a thin, retentive or liquid-proof course 12 which is used to give a smooth top 80 surface to the foundation layer, but more particularly to prevent any of the liquid or other ingredients of the superposed course from percolating downwardly into or becoming embedded in the underlying course 85 with its many voids and spaces, such intermediate stratum also forming a more or less clean cut division or partition between the other portions of the pavement, hence permitting or enabling the upper concrete 90 course 13 above it to unrestrainedly alter its dimensions under temperature modifications, thus in large measure, if not entirely, eradicating or eliminating its tendency to crack or divide into sections. Such intervening or 95 interjacent retentive or confining layer may be made of any appropriate material suitable for the performance of the functions which it is to carry out and may be composed of somewhat temporary ingredients or 100 substances which are not necessarily permanent, if desired. Such stratum may be composed of asphalt, oil, tar, water-proof paper or fabric, straw and tar, sawdust and tar, and many other substances which will readily suggest themselves to persons trained in 105 this industry.

Such retentive or separating layer may be applied in any one of several different ways depending upon the nature of the material 110 used for such course. Asphalt, oil, tar, or the like may be used alone or mixed with

other materials, and such interposed course or layer may be applied by spraying, painting, flooding, or by the application of pressure, as by rolling, it being desirable that 5 the top surface of such separating stratum should be substantially, though not necessarily exactly, smooth. Obviously, the thickness of such layer would depend upon the substance or materials of which it is composed, but ordinarily it would be comparatively thin.

This top layer of concrete may be composed of cement and crushed stone with or without sand or other relatively-fine material 15 and may be of any thickness, say of from about 2 to 6 inches according to the nature of the road and the traffic to pass over it. Such concrete is, of course, applied wet with a substantial part composed of comparatively 20 thin or liquid grouting which, if permitted, as by the absence of the middle course, would flow down leaving the top layer to percolate into the interstices of the foundation stratum, thus not only causing an undesirable absence 25 of such grouting in the wearing or surface course, but causing a more or less positive interlocking between the two courses when such cement hardens. This intermediate or retentive layer between the other courses 30 forms a relatively-smooth matrix for the concrete above it preventing separation of the grouting therefrom, avoiding the interlocking 35 of the upper and lower layers, and causing a positive division between itself and the bottom surface of the top course. It will be appreciated, therefore, that such interjacent retentive layer forms a comparatively-smooth uniform depository on which the concrete top layer may be spread, and it prevents the fine or liquid portions of such top 40 course from escaping into the spaces or voids of the lower or foundation layer. It, therefore, causes the retention of such fine and liquid portions of the concrete in the top 45 layer near the finished surface of the road, thereby giving it greater strength and wear-resisting qualities by reason of adequately cementing or binding together the particles contained in such top course. Stated somewhat 50 otherwise, this intermediate layer assures a practically-uniform texture of the top layer or wearing stratum of the pavement and by its employment proper control may be had of the thickness or consistency 55 of the material for the top stratum before, during, and after the laying. The upper layer of concrete may be treated with oil, tar, or other material, if desired, but it will be found that, under my improved construction,

such top layer of concrete may be more easily 60 and better floated to attain the best traffic surface.

A pavement of this kind has a distinct parting line or division between the foundation layer and the top stratum of concrete, 65 thus, to a considerable extent, if not entirely, doing away with the cracking or breaking of the top layer which by the employment of the middle stratum may be formed of practically uniform thickness, the intermediate 70 layer to a certain extent at least acting as a cushion for the top wearing surface.

Repairs to the top portion of such a pavement may be more easily effected than has heretofore been possible because any section 75 of the top layer may be readily removed and replaced with new concrete without fracture or disturbance of the bottom or lower layer.

It is to be understood that this invention is not necessarily limited and restricted to 80 the precise and exact features of construction illustrated and described in detail because these may be varied within comparatively wide limits without departure from the heart and essence of the invention and without the 85 sacrifice of any of its substantial benefits and advantages. In other words, the invention is susceptible of a variety of embodiments all incorporating its main and underlying principles but differing more or less in structure 90 and in the method of laying the pavements.

One especially important feature of the invention is the maintenance of the grouting in the top or surface layer of the pavement and as a result of this the various advantages 95 specified accrue, among which may be mentioned the employment of a minimum amount of cement, which, however, is used to a maximum beneficial effect.

I claim:

A pavement comprising in combination, a foundation stratum having substantial voids and composed of a mass of bodies of substantial size compacted to provide a smooth top surface consistent with the nature of such stratum, an intermediate retentive layer thereon with a substantially smooth top surface practically liquid tight at least when laid, and a top stratum of concrete having a substantially flat bottom surface, 105 resting on said intermediate layer and retaining substantially all of its original grouting and free from anchorage to the underlying strata, whereby comparatively unrestrained expansion and contraction movements of said top stratum are possible independently of the underlying strata.

NORMAN DE WIND.
